PROPANE DEWAXING

Henry O. Forrest, Teaneck, N. J., assignor to
Standard Oil Company, Chicago, Ill., a corpora-
tion of Indiana

Application March 8, 1935, Serial No. 10,060

4 Claims. (Cl. 62—170)

This invention relates to the separation of wax from mineral oils by the use of liquefied normally gaseous diluents such as propane and it pertains more particularly to an efficient 5 method of utilizing the refrigeration value of cold products and a method of continuously and countercurrently cooling an oil-wax slurry.

The object of my invention is to avoid the necessity of scraped surface chillers and at the 10 same time to utilize the refrigeration value of cold filtrate for cooling further amounts of diluted oil-wax mixture.

A further object is to provide a method and means for continuously chilling a propane-oil 15 mixture by self-refrigeration in a plurality of stages without shock chilling in any stage. Other objects will be apparent as the detailed description of my invention proceeds.

In practicing my invention I employ a relatively 20 large number of chilling stages so that there will be no appreciable pressure drop between any stage and the next succeeding stage, the wax slurry being introduced at the bottom of each stage and from the top of said stage to the 25 bottom of the next stage so that the summation of the heads of liquid in the various stages and the pressure drop due to the flow through the pipes connecting the various stages are substantially enough to account for the total pressure 30 drop throughout the cooling system. In order to utilize the refrigerative value of the cold filtrate, I pass said filtrate through coils in the vapor space of each chilling stage consecutively from the coldest to the warmest therefore, so that in each stage there will be about the same temperature differential between the propane-oil mixture and the cooling coils in the vapor space. The cooling in each stage is effected by the vaporization of propane from the 35 mixture, the propane vapors being condensed on the coils in the vapor space so that the condensate falls back into the liquid like rain, thus not only cooling the liquid but maintaining a constant diluent ratio.

The invention will be more clearly understood 40 from the following description read in connection with the accompanying drawing, which forms a part of this specification and in which I have shown a diagrammatic plan of my improved system with parts thereof shown in vertical section.

The oil to be dewaxed may be a distillate or 45 residual stock from any type of a crude petroleum or it may be any other wax-bearing oil which 50 may be subject to the propane dewaxing proc-

ess. In my preferred example I will describe the dewaxing of an S. A. E. 50 Mid-Continent distillate lubricating oil stock. I will describe the use of propane as a preferred example of my refrigerant, but it should be understood that other normally gaseous refrigerants may be used. 5

The waxy oil stock from storage tank 10 is forced by pump 11 through line 12 to oil-propane mixer 13 where it is admixed with propane from line 14 and storage tank 15. If the oil is not at a sufficiently high temperature to bring about the complete solution of the waxy 10 oil in the propane, a heating means may be supplied in the mixer or heat exchange devices may be employed in lines 12 or 14. The warm solution of waxy oil in propane, preferably employing about two volumes of propane per volume of oil, is introduced by pipe 16 at the base of the first cooling stage 17.

Each of the cooling stages is carried out in 20 a pressure vessel 18 which is surrounded by suitable insulating material. An overflow pipe 20 conveys liquid from an intermediate point of the pressure vessel to the bottom of the next vessel. The flow of liquid through line 20 is 25 regulated by valve 21 which is in turn controlled by a float device 22 which is illustrated as being mechanically connected to the valve, but which in actual practice would be connected to the valve through a magnetic clutch so that 30 there would not have to be a packed joint.

The second stage of the cooling process is effected in pressure vessel 23 which is identical in structure with vessel 17. The last steps of the cooling process are effected in chambers 24 and 35 25. The total number of chilling stages will depend somewhat upon the nature of the oil to be chilled, the desired pour points of the finished oil, etc. and will also depend on whether or not wax crystallization regulators such as described in Davis Patent No. 1,815,022, MacLaren Patent No. 1,963,917, etc. are used. In general, I may employ from six to twelve of such stages and in the present example I prefer to employ ten stages and to effect a pressure drop of about 45 ten to twelve pounds per stage. The oil-wax slurry leaving the final stage 25 is conducted through line 26 to the base of chiller 27. Propane from storage tank 15 is conducted through line 28 and line 29 to cold propane storage tank 30 50 55 wherein it is flash chilled, and it is then introduced through line 31 and valve 32 into the upper part of chiller 27, the amount of cold propane being controlled by any suitable mechanism or valve 32. Propane is removed from chiller 27 55

through line 34 in amounts equivalent to the amounts introduced so that the ratio of propane to oil-wax mixture may be held constant. The cold propane is preferably introduced on bubble 5 plate 35 and it passes therefrom through downcomer 36 to bubble plate 37 before coming in direct contact with the cooled wax slurry. Propane vapors bubbling up under caps 38 are partially condensed in the cold propane and by their 10 condensation they give up enough heat to bring this cold propane into equilibrium with the temperature of the cold wax slurry, thereby avoiding shock chilling when the cold propane passes through downcomer 39 into the body of the 15 chilled oil-wax mixture.

The chilled slurry from chiller 27 is passed through line 40 to a storage tank 41 which is connected by line 42 to the holding compressor gas line 43. Slurry from tank 41 is forced by pump 20 44 or by fluid pressure into continuous filter 45, the wax cake being withdrawn through line 46 by pump or screw conveyor 47 through line 48 into wax melter 49 which is heated by closed steam coil 50. The wax is withdrawn through 25 line 51 and the propane is withdrawn at a pressure of about 200 pounds through line 52 directly to condenser 53.

The cold filtrate from filter 45 is passed by line 30 54 to filtrate collector 55 which is vented through line 66 to holding compressor gas line 43. This cold filtrate is forced by pump 57 under a pressure of about 200 pounds through line 58, coil 59, line 60, coil 61, line 62, coil 63, line 64, coil 65 and line 66 to high pressure propane still 67. Still 67 is provided with closed steam heating coil 68 which distills off the propane through line 69 which leads to condenser 70. The oil is passed from the base of still 67 through pipe 71 and reducing valve 72 and it is then introduced into 40 low pressure propane still 73 which is provided with steam coil 74. Finished oil is withdrawn from the base of the low pressure still through line 75. Propane from this still is withdrawn through line 76 to holding compressor gas line 45 43. Propane from cold storage tank 30 is introduced through line 77 to holding compressor gas line 43. Chiller 27 is connected through line 34 and line 78 to holding compressor gas line 43 and holding compressor 79'. Ordinarily valve 50 79 and valves 80 are closed, but provision is made so that propane may be withdrawn from any of the chilling stages and introduced through line 81 to holding compressor gas line 43. Suitable means (not shown) are also provided for draining liquids out of the various chilling stages, washing the filter with hot naphtha, etc. Such expedients and other expedients are well known to engineers skilled in the art and will therefore not be described.

60 The mixture of waxy oil and propane which was introduced through line 16 into stage 17 may be at a temperature of about 130° F. and there may be about a 35° to 40° F. temperature differential, so that the filtrate in coil 65 will be at a 65 temperature of about 90 to 95° F. The oil leaving the first stage through pipe 20 may be at about 120° F. and it is cooled in stage 23 to 110° F. by cold filtrate in coil 63 at about 80° F. With ten or twelve stages, I can thus reduce the 70 temperature of the propane-oil-wax mixture to about 40° F., or even lower, at which tempera-

ture it may be introduced into one or a plurality of evaporative chillers to which propane is added (illustrated in the drawing as chiller 27). If it is desired to maintain a constant temperature differential in the various stages I may supplement the filtrate with cold propane or other chilling medium. Likewise, I may supplement the countercurrent chilling action of the cold filtrate by removing some propane vapors through one or more of valves 80 and I may introduce cold 10 propane into one or all of these stages in the manner described in connection with chiller 27.

It should be understood that the depth of liquid in each chiller should balance the pressure from the preceding chiller (no pressure drop between steps) so that the effect is the same as if each stage were superimposed upon the preceding stage to give one high column. If a single column were used the liberated propane would cause too much turbulence,—this is avoided by 15 employing a long series of short columns as hereinabove described.

While I have described in detail a preferred embodiment of my invention, it should be understood that I do not limit myself to the above 20 details except as defined by the following claims, which should be construed as broadly as the prior art will permit.

I claim:

1. In apparatus of the class described, a plurality of closed chill chambers, means for introducing a liquid from an intermediate part of each chill chamber to the base of the next following chill chamber, means actuated by liquid level control for regulating the amount of liquid flowing from each chamber to the following chamber, and means at the top of each chamber for reducing the pressure in said chamber and causing the vaporization of propane on the surface of the liquid therein. 35

2. The apparatus of claim 1 wherein each of the chambers is provided with a cooling coil in the upper part thereof and wherein said cooling coils are connected in a series corresponding to the flow of liquids from each chamber to the 45 next.

3. In a process for separating wax from oil by means of a normally gaseous diluent such as propane, the method which comprises continuously introducing a propane solution of an oil-wax 50 mixture into a chilling stage, chilling said mixture in said stage by vaporizing propane therefrom, continuously transferring the chilled liquid from said stage to a second stage, chilling the liquid in the second stage by vaporization of 55 propane therefrom, and continuously transferring and chilling said solution in a plurality of further stages, the pressure at the bottom of each stage being substantially equal to the pressure at the top of the prior stage, accelerating 60 the vaporization of propane in each stage by passing a refrigerating fluid through the vapor space therein, and finally separating wax from 65 diluted oil.

4. The method of claim 3 wherein the refrigerating fluid is the cold propane oil solution separated from the wax and wherein the cold solution is passed countercurrent to the passage of the oil propane solution through the chilling 70 stages.

HENRY O. FORREST.
